UNITED STATES PATENT OFFICE.

ANDREW L. KLEIN, OF SAN FRANCISCO, CALIFORNIA.

SANITARY CLOSET-SEAT.

1,170,498.

Specification of Letters Patent. Patented Feb. 1, 1916.

Application filed May 4, 1915. Serial No. 25,791.

To all whom it may concern:

Be it known that I, ANDREW L. KLEIN, a citizen of the United States, residing at San Francisco, in the county of San Francisco 5 and State of California, have invented certain new and useful Improvements in Sanitary Closet-Seats, of which the following is a specification.

My invention relates to new and useful 10 improvements in sanitary toilet seats, the primary object of the invention being the provision of a seat pad applicable to seats of conventional structure and consisting of a plurality of layers of oiled or otherwise 15 chemically treated tissue paper or other suitable material.

A still further object of my invention consists in the provision of a novel, simple and effective means of detachably securing such 20 pads to toilet seats.

A still further object of my invention consists in forming the pads in such a manner that after use, the uppermost sheet may be 25 readily removed to expose a fresh and clean surface. And a still further object of my invention consists in constructing a sanitary seat pad of the above described character which may be folded to permit its shipment in compact form.

With these and other objects in view, my 30 invention will be more fully described, illustrated in the accompanying drawings and then specifically pointed out in the claims which are attached to and form a part of this 35 application.

In the drawings, Figure 1 is a side elevation of a conventional form of closet hopper showing my improved seat pad applied to a seat of conventional construction, Fig. 2 40 is a top plan view of a conventional toilet seat with my improved pad in place, Fig. 3 is a transverse sectional view taken on the line 3—3 of Fig. 2 showing the tab of the upper sheet of the pad bent up prior to removal of such sheet from the pad, Fig. 4 45 is a perspective view of one free end of one of the pad forming sheets showing the construction of the tab, Fig. 5 is a view corresponding to that shown in Fig. 2 and illustrating a slightly modified form of construction, Fig. 6 is a fragmentary perspective

view of the seat and pad showing the method of attaching the form of pad illustrated in Fig. 5, to the seat, Fig. 7 is a top plan view of a still further modified form of sanitary 55 seat pad construction, and Fig. 8 is a sectional view taken on the line 8—8 of Fig. 7, Fig. 8^a is a transverse sectional view taken on the line 8^a—8^a of Fig. 7.

In order to insure a clear and accurate 6 understanding of my improved sanitary seat pad and its manner of application, I have illustrated it in connection with a conventional form of toilet seat 10 supported in any suitable manner upon the usual hopper 65 11. The form of pad illustrated in Figs. 1 to 4 of the drawings includes a base portion 12, preferably formed of straw-board or other suitable similar material, cut into substantially U-shape to conform substantially 70 to the shape of the front and side portions of the conventional toilet seat, and being proportioned to extend substantially three-quarters or more of the way about the seat, leaving an opening at the back. This straw-board base is pressed or otherwise molded 75 to conform to the cross-sectional curvature of the upper face of the seat 10 to which it is to be applied and carries a plurality of layers of oiled or other suitably prepared 80 tissue paper 13, the peripheral edges of these sheets being stitched to each other and to the base by heavy threads 14. These sheets 13 of paper forming the body proper 85 of the pad, at their ends are extended, to form tabs or tongues 15 and each sheet is preferably provided with spaced lines of perforations 16 extending from the sides of one tab throughout the circumference of the pad to the corresponding sides of the 90 other tab. Because of this, the sheets may be successively removed from the pad by merely bending up one of the free tabs and exerting strain upon it to tear out the strip 17 formed between the lines of perforations. 95 After this strip has been torn out, it will be clear the side portions of the sheet may be readily folded down and torn away from the threads 14.

In order to secure the above described pad 100 to the seat 10, the base portion 12 of the pad is preferably provided at intervals with

transversely extending strips of sheet metal 19, the free ends of which extend below the sides of the pad before the latter is applied as shown in full lines in Fig. 3, being capable of being bent upwardly to engage against the lower face of the seat 10 as shown in dotted lines in the same figure. This form of fastening permits the application of the pad to seats of slightly different sizes and 10 conformations, as the base 12 of the pad while molded to a certain shape or size, is not so rigid as to prohibit or prevent its spreading to accommodate seats of somewhat different sizes and shapes.

15 In Figs. 5 and 6 of the drawings, I have illustrated a form of sanitary seat pad substantially the same as that shown in Figs. 1 to 4, with the exception that the pad therein shown is constructed to completely cover 20 the seat, being in the form of a closed substantially elliptical ring and including a straw-board base 20 supporting a plurality of sheets of oiled tissue paper 21. These sheets, as shown in Fig. 5, are endless and 25 are stitched to each other and to the base by threads 22 in the manner described previously. In order to provide for the ready removal of sheets from a pad of this nature, the sheets are provided with spaced U-shaped 30 clefts or incisions 23 and with a spaced series of perforations 24 connecting the incisions. By grasping one or more of the tabs or tongues 25 formed by the incisions 23, the central portion of the sheet may be readily 35 torn from the remaining portion and the remaining side portions then removed from the pad.

As a means for attaching this form of pad to the seat, I provide the base at suitable 40 intervals with a plurality of spring clips 26, the free ends of which are bent somewhat, as shown at 27 in order that they may engage beneath the side edges of the seat when the pad is forced down upon the seat and thus 45 automatically lock the pad in place.

In Figs. 7 and 8, I have illustrated a still further modified form of seat pad including a base 30 of straw-board or other suitable material corresponding to the base 12 in 450 that it is adapted to extend only a little over three-quarters of the way around the seat leaving the seat exposed at the back. This base however, is not curved transversely, but is flat as clearly shown in Fig. 8. The pad 50 in this figure includes two portions 31, each portion being secured to one side of the base 30. Each portion is made up of a plurality of superimposed layers of oiled paper, in the same manner as the other pads except 55 that their side edges are cut vertically and they are stitched to each other and the base by threads 32. The forward ends of the body portions 31 of the pad are spaced from each other and such ends are preferably cut 60 at an inclination as shown at 33 in Fig. 7,

each sheet, from the bottom up, being slightly shorter than the sheet below. The rear ends of the sheets are provided with tabs 34, corresponding to the tabs 15 of the form of my invention illustrated in Figs. 1 to 4.

The base 30 is preferably formed in two symmetrical portions, the forward ends of which are hingedly connected in any suitable manner as by a strip of fabric 35 secured to the lower faces of the base members at their forward ends by any suitable adhesive. Because of this, it is possible to fold the pad along its longitudinal axis for compact shipment or storage.

80 In view of the number of modifications which I have illustrated and described, it will be clear that my invention is susceptible to very many minor changes, and for this reason, I do not wish to be limited to any specific details of construction reserving the right to make any changes which may fall within the scope of the appended claims.

Having thus described my invention, what I claim and desire to secure by Letters Patent is:—

1. A sanitary pad for toilet seats including a substantially U-shaped base adapted to rest upon the front and side portions of a toilet seat, and a plurality of superimposed layers of oiled paper correspondingly shaped secured by their edges to each other and to the base, said sheets at their free ends being formed with extending tongues.

2. A sanitary pad for toilet seats including a substantially U-shaped base adapted to rest upon the front and side portions of a toilet seat, and a plurality of superimposed layers of oiled paper correspondingly shaped secured by their edges to each other and to the base, said sheets at their free ends being formed with extending tongues, and each sheet being formed with spaced series of perforations extending from the tongue at one end to that at the other.

3. A sanitary pad for toilet seats including a base adapted to rest upon a toilet seat, and a plurality of superimposed layers of paper secured by their edges to each other and to the base, each of the sheets being formed with a tongue and with lines of perforations extending longitudinally of the sheet from the sides of the tongue.

4. A sanitary pad for toilet seats including a base adapted to rest upon a toilet seat, and a plurality of U-shaped sheets of paper secured to the base and each terminating at its ends in rearwardly extending tongues.

5. A sanitary pad for toilet seats including a substantially U-shaped base adapted to rest upon the front and side portions of a toilet seat, and a plurality of superimposed layers of paper correspondingly shaped secured by their edges to each other and to the base, said sheets being formed with spaced

series of perforations extending from end to end of the sheets.

6. A sanitary pad for toilet seats including a base adapted to rest upon and be secured to a toilet seat, and a plurality of superimposed layers of paper secured by their edges to each other and to the base, each layer of paper being formed intermediate its width

with tongues which may be grasped to facilitate the removal of such layer.

In testimony whereof I affix my signature in presence of two witnesses.

ANDREW L. KLEIN. [L. s.]
